VACUUM CLEANER

Application filed April 30, 1926. Serial No. 105,780.

This invention relates to vacuum cleaners, and particularly to the combination of brushing and beating devices in the suction nozzle thereof.

5 The general objects of the invention are to provide in the suction nozzle of a vacuum cleaner an improved, rotatable, helical brush having a progressive sidewise brushing action on floor coverings to thoroughly brush 10 lint, ravelings and the like therefrom; and a circumferential series of freely rotatable beater rollers, also preferably arranged in a helical series, adapted to beat the floor coverings so as effectively to loosen the dirt therein.

15 A further object of the invention is to provide a device for combing the ravelings and the like out of the brush, whereby the suction can carry them to the usual receiver.

The foregoing and other objects are obtained by the construction illustrated in the accompanying drawings. It is to be understood that the invention is not limited to the specific form thereof shown and described herein.

25 Of the accompanying drawings:

Figure 1 is a sectional plan, partly broken away, through a cleaner nozzle embodying the invention;

Figure 2 is a section on line 2—2 of Figure 30 1; and

Figure 3 is a detail section on line 3—3 thereof.

Referring to the drawings, 10 represents the nozzle of a vacuum cleaner embodying the 35 invention. Journaled in the nozzle so as to operate in the inlet 11 thereof are drums 12, 12 which may be driven in any suitable manner, for example, by the central drive shown herein including a belt 13 trained over 40 a central pulley 14 connected to the drums.

The drive belt 13 may be driven from the shaft 24 by a pulley 25 thereon, shaft 24 being, for example, an extension from the rotor of the suction fan (not shown).

45 Drums 12 have helical undercut or dovetail slots 15, 15 therein, each adapted to receive a flexible brush 16 which may include a flexible vulcanized rubber base 16^a in which the bristles are set, the base being shaped to 50 be fitted in a slot 15 by sliding it endwise

therein, the outer end of each slot in the present form of the invention being open but being adapted to be closed as by a pivoted clip 17 arranged to swing across the open end of the slot.

The drum 12 also has freely journaled in the periphery thereof a helical series of beater rollers 18, 18 adapted effectively to beat a floor covering without destroying the same.

The floor covering to be cleaned is preferably first subjected to the brushing and beating actions and then to the suction action. Accordingly the suction is concentrated at the rear end of the inlet 11 by means of baffle 19, extending downwardly from the top wall 55 of the nozzle to adjacent the lower wall to provide a comparatively small suction opening as at 20. An arc-shaped plate indicated at 21 may be secured in the nozzle to provide a housing for the rotating drum 12 and to 60 brace the baffle 19.

The brush 16 will effectively pick up lint, ravelings and the like, but it has been found that the suction does not thoroughly clean the brush of the lint and ravelings. To the 65 end, therefore, that the brush will be kept clean at all times, combing devices 22, 22, are mounted on the lower end of the baffle 19, these devices being formed with teeth 23, 23 adapted to project into the outer portion of 70 the brushes 16 but to clear the beater rollers 18. Since the combing action of the teeth 23 takes place adjacent the restricted inlet 20, the suction current picks up the lint, ravelings and the like combed from the brushes. 75

The operation of the above-described mechanism will be understood from the foregoing. Briefly stated, it consists in connecting the cleaner to a source of power and moving the cleaner over the surface to be cleaned. 80 The beaters 18 thoroughly loosen the dirt, the brushes 16 further loosen the dirt and pick up the lint and ravelings, the combs 22 remove the lint and ravelings from the brushes and the strong suction current at 85 20 conveys the dirt, lint, ravelings, etc. to the receiver (not shown).

Modifications of the invention may be resorted to without departing from the spirit thereof or the scope of the appended claim. 100

What is claimed is:

A vacuum cleaner comprising a nozzle having an opening in the bottom thereof, a horizontal drum rotating in the opening, a helical brush on the periphery of the drum, a helical series of freely rotatable beater rollers in the periphery of the drum, the brush and rollers being operable by the drum to contact with the surface over which the cleaner is operated, said brush extending radially beyond said rollers an element arranged in the nozzle to provide with the adjacent nozzle wall a constricted suction inlet adjacent the rear of the opening, and a comb carried by said element adjacent the inlet arranged to engage in the outer portion of the brush and to clear the beater elements.
